UNITED STATES PATENT OFFICE.

JOSEPH RIDGE, OF CHICAGO, ILLINOIS.

NOISELESS SLATE.

SPECIFICATION forming part of Letters Patent No. 278,744, dated June 5, 1883.
Application filed March 7, 1883. (No model.)

To all whom it may concern:

Be it known that I, JOSEPH RIDGE, of Chicago, county of Cook, and State of Illinois, have invented new and useful Improvements 5 in Noiseless Slates, of which the following is a full and complete description, reference being had to the accompanying drawings.

My invention relates to a method of muffling slates, wherein the cloth or strip is so secured 10 in the frame that a better cushion or more deadened effect is secured than by the usual method of drawing the cloth tightly on the frame or supplemental strip. My invention also relates to cheapening the operation of 15 muffling and to giving the slate a neater appearance.

With reference to the drawings, Figure 1 represents the slate with a portion broken away. Fig. 2 is a section of the frame before 20 the muffler is applied. Fig. 3 is a cross-section of the finished slate through broken line, Fig. 1; and Fig. 4 is an edge elevation.

A represents the slate proper. B is the frame. a represents notches or recesses along 25 the outer margin of the frame. C represents the muffling-strip, of cloth or other pliable and noiseless material, and b represents keys or wedges.

As perhaps the best method of securing the 30 keys in the notches, the latter are dovetailed. The muffling-strip is somewhat greater in width than the thickness of the frame, and is drawn tightly around the outer surface of said frame, being forced at intervals into each notch 35 or recess, where it is secured by keys b. The strip C being wider than the thickness of the frame, it is so adjusted thereon that its edges project on each side, forming a narrow pliable cushion or rib, by which the frame is protected 40 from contact with the desk, and the consequent noise avoided. As the most rapid and easy manner of inserting the keys, the latter are made of strips of sheet metal covered with cloth and cut into proper size. They may then be 45 curved and shortened, so they will enter the

outside or narrowest part of the notch, and, being forced in on strip C, may be straightened by pressure and thus firmly secured, at the same time securing said strip C.

Solid or inflexible keys may of course be 50 driven into the notch at the side of the frame, the muffling-strip being first pressed down into the notch; or said strip C may be secured in the notches in any other manner, the latter serving to secrete said fastenings and to 55 prevent their contact with the disk.

It is evident that the muffling-strip being drawn tightly in circuitous or zigzag directions around the frame, and its central portion being secured as with the keys, the tension prevents the edges of said strip from being crushed or flattened down to remain so, but will stand out, forming the desirable cushion or support 60 that renders the slate more noiseless than when the covering is drawn tightly and flatly on the 65 frame.

The notches or recesses may of course be longer and located farther apart than relatively shown in the drawings, with substantially the same effect. The result of the series 70 of notches with the strip c inserted is to give the frame a scalloped appearance, thus adding to its neatness.

Having thus fully described my said invention, what I claim, and desire to secure by Letters Patent, is—

1. The slate-frame provided with notches or recesses around its outer surface, in combination with the muffling-strip C and keys b, or other fastening devices, substantially as and 80 for the purpose specified.

2. In combination with a slate-frame, the band or ribbon like strip C, secured in zigzag or serpentine directions by removing sections of said frame and clamping said strip therein, 85 substantially as and for the purpose set forth.

JOSEPH RIDGE.
